UNITED STATES PATENT OFFICE.

WILLIAM F. CHINIQUY AND WILLIAM O. WINCH, OF CHICAGO, ILLINOIS.

MEANS FOR HANDLING RODS FOR HAT-DRYING APPARATUS.

1,249,029.

Specification of Letters Patent.

Patented Dec. 4, 1917.

Application filed February 11, 1915. Serial No. 7,497.

To all whom it may concern:

Be it known that we, WILLIAM F. CHINIQUY and WILLIAM O. WINCH, citizens of the United States, residing at Chicago, in the county of Cook and State of Illinois, have invented certain new and useful Improvements in Means for Handling Rods for Hat-Drying Apparatus, of which the following is a specification.

10 This invention relates to hat drying apparatus and more particularly to means for handling and washing the rods or supports upon which the treated hats are disposed during the drying operation. One of the 15 objects of our invention comprises the provision of a suitable receptacle wherein the various parts of the conveyer mechanism that come in contact with the hats being dried are automatically discharged for the 20 purpose of cleaning the same.

Still another object is the provision of a suitable slideway into which the hat supporting elements or rods are discharged after passage through the heated chamber 25 preparatory to depositing the same in the cleaning or washing receptacle.

A still further object of our invention is to construct an apparatus of the class described that will be simple in construction 30 and operation, easy to operate and inexpensive to manufacture.

We accomplish the above and other objects familiar to those skilled in this art by the means and in the manner hereinafter 35 set forth, reference being had to the accompanying drawings wherein similar reference characters refer to similar parts throughout the various views.

Figure 1 is a longitudinal side elevation 40 of our invention.

Fig. 2 is a fragmentary end elevation thereof at the feed end of the apparatus.

Fig. 3 is a fragmentary front elevation of the mechanism shown in Fig. 1.

45 Fig. 4 is a fragmentary top plan of the discharge end of the conveyer.

Fig. 5 is an elevation of the mechanism shown in Fig. 3.

Fig. 6 is a fragmentary front elevation 50 of the rod discharge mechanism and cleaning receptacle.

Fig. 7 is a transverse vertical section taken on line 7—7 of Fig. 6.

Primarily, our hat drying apparatus comprises a longitudinally disposed compartment, substantially rectangular in cross section, being of any desired dimensions to suit the individual case. This compartment is preferably suspended from the ceiling of the room in which it is installed, being effectively heated by causing a draft of hot air or steam to pass therethrough. The compartment is preferably made of sheet metal bent to a hollow rectangular form and is of a length sufficient to entirely dry the hats during their transit therethrough on the conveyer.

The means for conveying the hats through this heated compartment consists of an endless conveyer comprising two parallel simultaneously driven link belts or chains 10, that are suitably supported and guided through the heated compartment preferably by means of idlers 10^b or in any other suitable manner. Interposed at intervals between the links of 75 these chains 10, are a plurality of hook-shaped carrier links 10^a, that afford a means for supporting a plurality of transversely disposed removable parallel rods 11, (Fig. 1).

The rods 11, are adapted to be picked up 80 at the feeding or receiving end of the apparatus (Figs. 2 and 3), carried through the compartment on said conveyer and discharged therefrom at the opposite end thereof (Figs. 4 and 5) where they are deposited 85 in a suitable washing vat (Figs. 6 and 7).

The feeder mechanism consists of a suitable table 12, comprising horizontal top members 12^a, vertical standards or legs 12^b and transverse ties 12^c. Transverse to the 90 members 12^a and secured preferably to the tops thereof are suitable guides or brackets in which bearings 13 are adjustably mounted, which latter are adapted to support a longitudinally disposed shaft 14, extending 95 substantially parallel with the top of the table, while keyed to each end of said shaft are suitable sprockets 15, over which the chains of the conveyer are adapted to travel. Mounted upon brackets 16, bolted to the top 100 members 12^a just in front of the sprockets 15, are inclined chutes or guideways 17, upon

which the rods 11 are placed and from which they are removed one at a time by the hooked links 10^a of the conveyer. Suitable substantially V-shaped brackets 18 are secured to the forward side of the legs 12^b, and are adapted to support the rods 11, prior to their being placed upon the chutes 17.

Upon reaching the discharge end of the heating compartment the conveyer travels 10 over a sprocket wheel 19, mounted on the ends of a shaft 19^a, which is suitably journaled in bearings 19^b, secured to brace members 19^c, which latter are bolted to the vertical sides of the compartment. Guide plates 15 20, are secured between the sprocket wheels 19 and the adjacent side walls of the compartment, and extend from points a suitable distance inside the compartment toward the adjacent end thereof and gradually converge 20 to points past the outer segments of sprockets 19. The upper portion 20^a of each plate is preferably bent laterally in a horizontal plane and then extends inwardly and then down, to form a depending flange apron 20^b, 25 through a portion of which the conveyer chain is adapted to pass. An opening 20^c is cut in the lower edge of the depending portion 20^b to admit of the passage of the chain and hooked links. A bent or curved rod 21, held in place by suitable transverse pins 21^a, that project inwardly from the vertical walls of the compartment is so disposed therein that its curvature is substantially parallel or concentric with the contour of the 30 sprocket 19 so that during the movement of the conveyer the rods are adapted to be retained upon the hooks until the proper time for their discharge. The lower end 21^b of the rod 21 is straightened and is preferably 35 inclined tangential to the arc described by the curved portion thereof, and as the rods 11 are discharged from the chains they roll down the inclined portion 21^b to the receiving chute of the washing vat.

40 The washing vat preferably comprises a suitable receptacle 22 that is supported upon a rectangular shaped open frame 22^a mounted upon legs or otherwise, the upper portion of said receptacle being hopper shaped and the lower portion or bottom being segmental shaped substantially as shown in Fig. 7 of the drawings. Extending downwardly from the lower inclined end of rod 21, to a point above and adjacent the open end of the receptacle 21^b are substantially vertically disposed parallel plates 23 in which serpentine paths or grooves 23^a are formed that are faced with strips of leather, or other suitable sound deadening material 23^b. This 45 serpentine groove permits the gravitation of the rods at a retarded speed and avoids the clatter and noise incident to the falling of said rods through a straight path.

50 Mounted upon a longitudinally disposed

horizontal rock shaft 24, journaled at its ends in bearings 22^c on frame 22 are transversely disposed horizontal arms or levers 25 that extend transversely across the hopper of the receptacle and are adapted to receive the rods 11, as they gravitate from the lower discharge end of the serpentine grooves. The ends of said rock-shaft are provided with counter-balanced levers 24^a so that after a quantity of said rods are received upon said arms they will tilt and deposit the same in the washing receptacle.

Extending parallel to the shaft 24, is a similar shaft 26, journaled at its ends, and at suitable points intermediate thereto in bearings 26^a bolted to the side of the frame 22^b; said shaft is provided at one end with a suitable crank 26^b, and a pawl and ratchet mechanism 26^c and intermediate its bearings said shaft 26 is provided with pulleys or reels 27, upon which strips of suitable flexible material 28 are secured and wound and which pass up over rollers 29, mounted upon the longitudinally disposed front edge 22^b of the vat 22, and have their opposite ends secured to the frame after passing over the shaft 24. A plurality of substantially parallel bars 30, are secured to the front edge of the frame and incline downwardly a short distance to form a shelf upon which the hat supporting rods are placed after being washed. The central portion of said bars 30 is bent upwardly and then downwardly in a vertical direction to form a stop 30^a, against which the rods will rest and drip, the lower ends of said bars being secured in any suitable manner to the cross piece 22^d, of the tank supporting frame. Directly under these bars a drip pan 31 is provided to receive the drip from the washed rods.

The receptacle 22 is preferably partly 105 filled with a cleansing fluid and the pawl and ratchet mechanism released so as to immerse the strips 28 therein. The hat carrying rods are deposited upon the arm 25 until a sufficient number has been received 110 to overbalance the weight whereupon the shaft 24 will rock and cause the rods to fall into the receptacle and be caught by the strips 28. Agitation is caused by rotating the shaft 26 by means of the crank 26^b a 115 short distance in one direction and then in the opposite direction permitting the rods to tumble over each other and rub together for the purpose of thoroughly cleansing them.

Pan 31 is provided in its bottom with a suitable drain pipe 32, and an overflow pipe 33 is tapped into the receptacle for the purpose of preventing too large a quantity of 125 cleansing fluid from being placed in the latter.

In operation the rods are placed upon the feeding chute 17 from which they are picked

up one by one in substantially successive order by the hooks upon the conveyer, which latter moves them upwardly into and through the heated compartment. The hats 5 are placed upon these rods by operatives standing at the feed end of the conveyer and are preferably arranged in rows, twelve in each row. The heated compartment is closed at the opposite end and is provided with a 10 suitable injector, whereby hot air is blown into the interior of said compartment. The hats travel through the compartment at a very slow speed and upon reaching the opposite end are discharged therefrom upon a 15 downwardly and outwardly inclined trough or chute 34 whence they slide upon a suitable table or other receptacle. The rods continue their travel with the conveyer until the lower end of the rod 20 is reached where 20 they leave the hooks and slide into the serpentine guideway 23 down to the arms prior to being immersed and cleansed.

We claim—

1. Means for receiving and washing rods 25 carried by a conveyer comprising a washing receptacle, means for directing said rods from said conveyer to said receptacle, a device interposed in the path of said rods and from which they are discharged into said 30 receptacle, and means for agitating the rods within said receptacle comprising a plurality of parallel flexible strips secured at one of their ends, drums upon which the opposite ends of said strips are adapted to 35 be wound, and means for rotating said drums.

2. Means for receiving and washing rods 40 carried by a conveyer comprising a washing receptacle, means for directing said rods from said conveyer to said receptacle, a device interposed in the path of said rods and from which they are discharged into said 45 receptacle, and means for agitating the rods within said receptacle comprising a plurality of parallel flexible strips secured at one of their ends, drums upon which the opposite ends of said strips are adapted to be wound, means for rotating said drums and pulleys mounted on said receptacle 50 adapted to support said strips between their secured ends and said drums.

3. Means for receiving and washing rods 55 carried by a conveyer comprising a washing receptacle, means for directing said rods from said conveyer to said receptacle, a device interposed in the path of said rods and from which they are discharged into 60 said receptacle, and means for agitating the rods within said receptacle comprising a plurality of parallel flexible strips secured at one of their ends, a rotatable shaft journaled opposite the secured end of said strips, drums secured upon said shaft upon which said strips are adapted to be wound,

means for actuating said shaft, and pulleys 65 mounted on said receptacle adapted to support said strips between their secured ends and said drums.

4. Means for receiving and washing rods 70 carried by a conveyer comprising a washing receptacle, means for directing said rods from said conveyer to said receptacle, a device interposed in the path of said rods and from which they are discharged into 75 said receptacle consisting of a rock shaft journaled on said receptacle, and lateral arms mounted on said rock-shaft and extended across the lower ends of said directing means.

5. Means for receiving and washing rods 80 carried by a conveyer comprising a washing receptacle, means for directing said rods from said conveyer to said receptacle, a device interposed in the path of said rods and from which they are discharged into 85 said receptacle, and means for agitating the rods within said receptacle, said means also adapted to elevate said rods and remove the same from said receptacle, and a plurality of transversely disposed bars adjacent said 90 receptacle in position to receive said rods when elevated by the agitating means.

6. Means for receiving and washing rods 95 carried by a conveyer comprising a washing receptacle, means for directing said rods from said conveyer to said receptacle, a device interposed in the path of said rods and from which they are discharged into 100 said receptacle, and means for agitating the rods within said receptacle, said means also adapted to elevate said rods and remove the same from said receptacle, and a plurality of transversely disposed parallel bars adjacent said receptacle in position to receive 105 said rods when elevated by the agitating means.

7. Means for receiving and washing rods 110 carried by a conveyer comprising a washing receptacle, means for directing said rods from said conveyer to said receptacle, a device interposed in the path of said rods and from which they are discharged into 115 said receptacle, and means for agitating the rods within said receptacle, said means also adapted to elevate said rods and remove the same from said receptacle, and a plurality of transversely disposed parallel bars adjacent said receptacle, the outer portions are bent upwardly to form a stop, said bars being disposed in position to receive said rods 120 when elevated by the agitating means.

8. Means for receiving and washing rods 125 carried by a conveyer comprising a washing receptacle, means for directing said rods from said conveyer to said receptacle, a device interposed in the path of said rods and from which they are discharged into said receptacle, and means for agitating the rods

within said receptacle, said means also adapted to elevate said rods and remove the same from said receptacle, and a plurality of transversely disposed bars inclined downwardly from said receptacle in position to receive said rods when elevated by the agitating means.

In witness whereof, we have hereunto set

Copies of this patent may be obtained for five cents each, by addressing the "Commissioner of Patents, Washington, D. C."

our hands and seals this 6th day of February, 1915.
